[57] ABSTRACT

A thin and narrow vibrator belt unit for use on automatic massaging machines which make use of conventional flexible U-shaped vibrator belts serves to impart deeper massage penetration and massage concentration to a small desired area. The thin and narrow vibrator belt unit includes a thin and narrow flexible belt portion and two larger free ends. An easy attaching and intentional removal means to and from a massaging machine is an integral part of the larger free ends of the thin and narrow vibrator belt unit.

1
VIBRATOR BELT

FIELD OF THE INVENTION

The present invention relates to vibrator belts, sometimes termed massaging belts, and particularly to a distinct vibrator belt unit for use on automatic massaging machines which make use of conventional flexible u-shaped vibrator belts.

DESCRIPTION OF THE PRIOR ART

A typical conventional vibrator belt or massaging belt is a wide belt with two smaller free ends and made out of suitable materials, leather being common. In each free end of a conventional vibrator belt is usually a thru hole as a means for attaching and removal to and from the massaging machine. The thru hole provided usually fits over the end of a shaft or rod extension of the massaging machine. The said end of a shaft or rod extension is usually equipped with a latching or locking means to lock in place the attached vibrator belt unit to the massaging machine.

The types of vibrator belts available, because of their wide widths, are subject to the disadvantages of not being able to impart deeper massage penetration and concentrate the massage to a small desired area. The known types of vibrator belts are also subject to some disadvantages including weight and expense.

SUMMARY OF THE INVENTION

Among the important objects of the present invention are to provide a distinct improved vibrator belt unit for use on massaging machines; to provide a vibrator belt capable of permitting deeper massage penetration; to provide a vibrator belt capable of concentrating massage to a small desired area; and to provide a vibrator belt unit which is light in weight and inexpensive.

The invention together with the above and other objects and obvious advantages may be better understood with reference to the following detailed description and illustrated in the accompanying drawings wherein:

BRIEF DESCRIPTION OF THE DRAWING

FIG. 1 is a simple perspective view of a massaging machine with the present invention of a thin and narrow vibrator belt unit with the two larger free ends attached in place;

FIG. 2 is a view of the thin and narrow vibrator belt unit; and

FIG. 3 is a side view of one free of the thin and narrow vibrator belt unit.

DESCRIPTION OF THE PREFERRED EMBODIMENTS

Referring now to the drawings, therin illustrated a new and distinct vibrator belt unit 7 as shown attached to a massaging machine 8 through the massaging machine means of vibrator belt attachment 9.

2

The free ends of the thin and narrow elongated cylindrical vibrator belt unit 7 having a cross-sectional diameter of about one-half inch and having enlarged flattened opposite ends 10 contains the attaching and intentional removal means 11 of the thin and narrow vibrator belt unit 7 to and from the massaging machine 8 means of attachment 9.

The attaching and intentional removal means 11 of the thin and narrow vibrator belt 7 are thru holes not necessarily round in shape and can be any number that is practical and economical to produce.

Although the present invention has been described with reference to a very simple illustrative embodiment, it should be understood that other modifications can be devised that will fall within the scope of the principles of this invention.

What is claimed and desired to be secured by letters of patent of the United States is:

1. A vibrator belt intended for use on a vibrating type massaging machine comprising a thin and narrow flexible elongated cylindrical body member terminating at opposite ends in substantially identical end portions, each end portion formed integrally with the body member as enlarged substantially flat generally elongated rectangular end portions having a width greater than the diameter of the body member, and a plurality of longitudinally aligned spaced apart apertures extending transversely through each end portion, the apertures in the first end portion being identical to the apertures in the second end portion and identically disposed and oriented in each end portion, the apertures in each end portion being of different cross-sectional areas and progressing from an aperture having the largest cross-sectional area disposed furthest from the outermost end of the end portion to an aperture having the smallest cross-sectional area disposed nearest the outermost end of the end portion, the apertures adapted to attach the vibrator belt to suitable drive terminals on the massaging machine.

2. The vibrator belt as set forth in claim 1 wherein the body member has a cross-sectional diameter of about one-half inch.

3. The vibrator belt as set forth in claim 2 wherein the apertures disposed in each end portion are of a circular cross-section, the diameter of the aperture furthest from the outermost end of the associated end portion being larger than the diameter of the aperture disposed nearest the end of the outermost end portion, and an aperture disposed intermediate said apertures of a diameter less than the first mentioned aperture and greater than the second mentioned aperture, the third mentioned aperture being disposed exactly intermediate the first and second mentioned apertures such that the third mentioned aperture is equally spaced from both the first and second mentioned apertures.
